UNITED STATES PATENT OFFICE.

EDMUND BURY, OF PHILADELPHIA, PENNSYLVANIA.

SUMMER-CAR.

SPECIFICATION forming part of Letters Patent No. 769,301, dated September 6, 1904.

Application filed February 6, 1904. Serial No. 192,361. (No model.)

To all whom it may concern:

Be it known that I, EDMUND BURY, a subject of the King of Great Britain and Ireland, residing in the city and county of Philadelphia, in the State of Pennsylvania, have invented certain new and useful Improvements in Summer-Cars, of which the following is a full, clear, and exact description, reference being had to the accompanying drawings, of

10 which—

Figure 1 is a side elevation of a car, showing my invention applied thereto. Fig. 2 is a section as on line xx , Fig. 1. Fig. 3 is a similar section as on line yy , Fig. 1. Fig. 4 is a perspective view of a portion of the operating mechanism. Fig. 5 is a perspective view of one of the uprights of the car, showing the bar pivoted thereto. Fig. 6 is a perspective view of a portion of the car-body, 20 showing portions of the mechanism.

This invention relates to improvements in summer-car construction; and its object is to provide a simple, effective, and safe mechanism or device whereby the side exits of such 25 cars may be readily opened and closed from either the front or back platform of the car by the conductor or other official.

The invention is applied more especially to the type of summer-cars in which the seats 30 extend across the car and the entrance thereto and exit therefrom is at the sides of the car through passages between vertical uprights or posts of the car and from which passages the passenger steps onto the running-board 35 of the car and thence to the street when leaving the car.

The invention consists in providing, pivoted to the uprights of the car, respectively, bars of such length that when in a horizontal position 40 they will form a continuous bar across the passages between the uprights, but when rotated to vertical position will be substantially in line with said uprights, and so out of the way of the passengers. To a short end 45 of each of these bars is connected a rod, which in turn is connected to a bar running longitudinally of the car and adjacent to the lower portion of the car-body, which latter bar is adapted to be forwardly and upwardly (and 50 the converse) reciprocated by suitable mech-

anism from either end of the car, whereby the bars pivoted to the uprights are rotated on their respective pivots to horizontal position (or returned to the vertical position) at the will of the operator.

55

The invention also consists of certain features and details of construction hereinafter pointed out.

In the drawings, A indicates the car, having the usual uprights or posts 1 and seats 2 60 in line therewith.

3 is the running-board—that is, the step—of the car, which extends longitudinally of the car and is suspended from a beam or support 4, on which the car-body is mounted.

65

5 represents the usual vertical hand-bars secured to the outer side of the uprights 1 in the well-known way—that is, said bars extend vertically parallel with the said uprights, but are held some distance away therefrom (so as 70 to leave considerable clearance therebetween) by suitable means, usually by turning inwardly the upper and lower ends of said hand-bars and securing the inturned ends to the uprights, as seen in Fig. 5.

75

A short distance above the lower end of each hand-bar 1 pivot to the upright between such hand-bar and the latter a bar 6, which when in vertical position is in line with said upright and with the hand-bar, as seen in Fig. 1. The 80 lower shorter arm of this pivoted bar is bifurcated at 7 for a purpose hereinafter appearing, and such lower end is pivotally connected with a rod 8, which latter is pivotally connected with a bar 9, extending longitudinally of the car adjacent to the outer face of the beam or support 4. Secured to the said beam 4 between it and said bar 9 and at suitable intervals apart are brackets 10, provided with upwardly and forwardly extending cam-slots 11, into which cam-slots, respectively, extend pins or projections 12, carried by the bar 9, all for a purpose hereinafter appearing. The bar 9 does not extend the entire length of 90 the car, but is connected at each end with a 95 lever 14 for operating the same.

85

90

95

Having now described the principal features of my invention, I shall proceed to describe the manner of using the same, at the same time describing certain details not hereto- 100

fore referred to. Assuming the parts to be in the positions shown in full lines in Fig. 1—that is, the bars 6 in the vertical position and the bar 9 in the retracted position, its pins 12 5 being at the lowest and most rearward position in said cam-slots 11 and the levers 14 in corresponding positions—if now it be desired to close the exits and entrances between the adjacent seats 2 of the car the operator (from 10 either the front or rear platform of the car) simply presses forward one of the levers 14, whereby the bar 9 is forced forwardly and upwardly, (being directed in proper direction by the cam-slots 11,) and thus the rods 8 are 15 moved correspondingly upwardly and forwardly, thus rotating the bars 6 on their pivots to the horizontal position. (Indicated by dotted lines in Fig. 1.) The outer free end of the long arm 6^a of each of said bars 6 then 20 rests between the bifurcations 7 of the short arm 6^b of the next bar 6 to the rear, thereby forming practically a continuous bar from front to rear of the car. The said bifurcations 7 are bent upwardly into U form, as seen, 25 so as to form a better rest for the ends 6^a and also so that the lower end of arm 6^b may pass around the lower end of the hand-bar 5. The levers 14 may be locked in either position by suitable means, such as a ratchet and pawl or 30 other means.

It will be seen that my device may be placed on summer-cars without alteration of the present construction and when not in use is entirely out of the way of the passenger when 35 entering or leaving the car and that it may be readily and efficiently operated by the conductor or other official from either platform of the car without taking his attention from his other duties in connection with the proper 40 operation of the car.

I would usually cover the bar 9 by securing to the outer side of the beam 4 adjacent to the outer face of the said bar 9 a board or the like 15, of course leaving slots between 45 said board and beam for the free operation of the rods 8.

Having thus described my construction, I claim as new and desire to secure by Letters Patent—

50 1. In a device of the character recited, the combination with the usual uprights, of the bars pivoted thereto respectively, the rods connected to said bars, below the pivot-point thereof, the bar extending longitudinally of the car adjacent to the lower portion thereof to which bar said rods are connected, the projections on said bar, the cam-inclines into which said projections respectively extend,

together with means adjacent to the ends of the car for longitudinally reciprocating said last-mentioned bar, substantially as and for the purpose set forth. 60

2. In a device of the character recited, the combination with the usual uprights, of the bars pivoted thereto respectively, and having 65 their lower ends bifurcated, the rods connected to said bifurcated ends of said bars, respectively, the bar extending longitudinally of car adjacent to the lower portion thereof to which bar said rods are pivotally connected, the projections on said bar, the cam-inclines on said car adjacent to said bar, into which cam-inclines said projections extend, together with means adjacent to either end of the car whereby said last-mentioned bar may 75 be reciprocated longitudinally, substantially as and for the purpose set forth. 70

3. In a device of the character recited, the combination with the usual uprights and the hand-bar on the outer side thereof, of the bars 80 pivoted to said uprights between the same and said hand-bars, respectively, the rods connected to said bars below the pivot-point thereof, the bar extending longitudinally of the car adjacent to the lower portion thereof, to 85 which bar said rods are connected, the projections on said bar, the cam-inclines carried by the car and into which cam-inclines said projections extend, together with means adjacent to the ends of the car for longitudinally reciprocating said last-mentioned bar, substantially as and for the purpose set forth. 90

4. In a device of the character recited, the combination with the usual uprights and the hand-bar on the outer side thereof, of the bars, 95 pivoted to said uprights between the same and said hand-bars, respectively, said bars having their lower ends bent outwardly and bifurcated, the rods connected to said lower ends of said bars, respectively, the bar extending longitudinally of the car adjacent to the lower portion thereof, to which bar said rods are connected, the projections on said bar, the cam-inclines carried by the car and into which cam-inclines said projections extend, together with means at either end of the car for longitudinally reciprocating said last-mentioned bar, substantially as set forth. 100

In testimony whereof I have hereunto affixed my signature this 12th day of January, 110 A. D. 1904.

EDMUND BURY.
